METHOD OF AND MEANS FOR GENERATING ELECTRIC OSCILLATIONS.

Application filed March 18, 1922. Serial No. 544,927.

To all whom it may concern:

Be it known that we, HOMER C. SNOOK and JOHN B. JOHNSON, citizens of the United States, residing at South Orange, in the county of Essex, State of New Jersey, and at Elmhurst, in the county of Queens, State of New York, respectively, have invented certain new and useful Improvements in Methods of and Means for Generating Electric Oscillations, of which the following is a full, clear, concise, and exact description.

This invention relates to a method of, and means for generating electric oscillations and more particularly to an arrangement for this purpose which embodies an electric discharge device having two elements.

Heretofore it has been proposed to generate electric oscillations by varying the heating current supply to the cathode of an electric discharge device, under the control of the current flowing through an oscillating circuit connected between the electrodes of the device. In this arrangement a portion of the current produced in the oscillating circuit is fed back to the cathode heating circuit, whereby the amplitude of the heating current for the cathode and hence the rate of emission of electrons therefrom are varied in synchronism with the oscillations generated.

By the present invention a similar result is obtained in an entirely different manner. The discharge device is provided with a cathode current conducting element of relatively large physical dimensions to which a current of large amperage is supplied. With large current flow through the conducting element a circular magnetic field will be set up in the space surrounding the electron emitter or cathode of the device, and the electrons tending to flow across the space, due to the potential difference supplied between the electron emitting cathode and the anode, will be deflected at right angles by this magnetic field and will tend to reenter the cathode. This will increase the space charge surrounding the cathode and hence increase the impedance of the device. The larger the current flow through the conducting element the greater is this effect.

In accordance with this invention a tuned circuit connected between the cathode and

anode of an electric discharge device is coupled to react upon the circuit supplying current to the conducting element, whereby the circular magnetic field surrounding the cathode and hence the deflecting effect of the field is varied. The space charge and hence the impedance of the device will be varied synchronously with the fluctuating current supplied by the oscillating circuit, and increments of energy will be supplied thereto to maintain it in oscillating condition.

One object of the present invention is to generate oscillations employing an arrangement which includes an electric discharge device having an abnormal space charge. Another object of the invention is to generate electric oscillations by varying the space charge of a two element electric discharge device.

The invention itself both as to organization and method of operation will be best understood by reference to the following description read in connection with the attached drawing, in which Fig. 1 illustrates an oscillator involving the invention; Fig. 2 is a cross-section of the discharge device shown in Fig. 1; Figs. 3, 3^a and 4 illustrate other circuit arrangements for practicing the invention.

Referring to Fig. 1 there is shown an electric discharge device comprising an evacuated vessel 1 enclosing an electron emitting cathode 2 and an anode 3. The enclosing vessel is preferably evacuated to such an extent that electron emission takes place independent of gas ionization. Current of large constant amplitude is supplied to the cathode or electron emitter 2 through a coil 4 by a source 5, whereby a constant circular magnetic field is produced within the device.

For example, with a discharge device having a tungsten cathode of twenty mils diameter and four inches long, an anode one and a half inches in diameter and six inches long, the current supplied to the cathode should preferably be of the order of twenty amperes. Space potential is supplied to the device by the source 6 over a path connecting it with the cathode 2 and anode 3. The constant current supplied to the cathode should be so chosen that a magnetic field of the desired value will be produced

within the device, to determine its critical voltage, i. e., the voltage at which space current will flow, and the potential of the source 6 should be such that the device operates on that portion of its characteristic where small variations in the intensity of the circular magnetic field produces large variations in the space current. By making the sources 5 and 6 adjustable, or using any well known means to secure adjustment of the current supplied by source 5 and the potential of the source 6 the magnetic field may be controlled. The anode is herein shown as cylindrical in form surrounding the cathode. While this construction is preferable, it is not essential to the operation of the device as contemplated by this invention. Included in the space current path is an inductance coil 7 shunted by a condenser 8. The coil 7 is inductively coupled to the coil 4 included in the supply circuit for the cathode 2. In order to obtain a phase relation between the oscillating current fed back and the space current in the device, whereby energy may be supplied to the tuned circuit the coils 4 and 7 should be loosely coupled. In this manner the leakage inductance of the coil 4 may be made great enough to produce a phase difference between the space current and the oscillating current flowing through the tuned circuit such that sustained oscillations may be generated.

As shown in Fig. 2 when current of large amperage is supplied to the hot wire or electron emitter 2 constituting the cathode of the electric discharge device 1, a circular magnetic field indicated by the arrows *a* surrounds the wire 2. This field will cause the electrons 12, as they tend to flow radially toward the anode 3, to be deflected in a direction at right angles to the magnetic field and hence tends to force them back to the emitter 2. The space charge surrounding the electron emitter and hence the impedance of the device will be thereby increased.

The cathode 2 as illustrated in this figure, may consist of a single element extending axially of the evacuated vessel or a plurality of filaments, such as are ordinarily used at the present time in electric discharge devices of well-known construction, may be similarly arranged and connected in parallel between the terminal contacts of the device.

The anode should preferably be concentric of the cathode and symmetrical thereto. Any unbalance or disturbance which occurs in the tuned circuit will produce a difference of potential across the condenser 8 and a discharge will take place through the inductance 7 to set up oscillations, the frequency of which will be determined by the constants of the tuned circuit. By adjusting the inductance 7, condenser 8, or both, the

constants of the tuned circuit and hence the frequency of the oscillations generated may be varied.

Due to the coupling between the coils 7 and 4, current variations will be induced in the circuit supplying current to the cathode, the frequency of which corresponds to natural period of the tuned circuit 7-8. This pulsating current will at one instant aid the current supplied to the cathode 2 by the source 5 and hence tend to increase the space charge of the device, and at the next instant will oppose the current normally supplied to the cathode and thereby decrease the space charge of the device. Obviously, the space charge as well as the impedance of the tube will vary at a frequency determined by the tuned circuit 7-8 and by means of the coupling between the coils 7 and 17 oscillations of this frequency may be supplied to a load circuit.

In order that sustained oscillations may be produced by the arrangement constituting this invention it is necessary that the oscillation voltage wave impressed upon the cathode and anode of the device 1, i. e., the space voltage, should be approximately 180° out of phase with the voltage wave produced in the oscillating circuit. Should the phase angle between the oscillating current produced in the tuned circuit and the pulsations flowing through the cathode supply circuit be less than that necessary to maintain oscillations, an adjustable inductance or variable condenser may be used, whereby the phase relation between these two waves may be adjusted. As shown in Fig. 3, the coil 7 is coupled to the coil 4 by means of a coupling circuit 9-11-13, the last mentioned being a variable phase adjusting inductance. In case it is desired to give the wave fed back a leading characteristic relatively to the space current, a variable condenser 14 may be included in a coupling circuit, as shown in Fig. 3a.

From the preceding description it will be seen that by using a two element electric discharge device having an electron emitting cathode of large current carrying capacity and supplying it with a constant current of large amplitude, a circular magnetic field is produced which serves to increase the space charge of the device. By properly selecting the amplitude of the current supplied to the cathode, the space charge of the device under normal conditions may be definitely determined and by producing an oscillating current and impressing it upon the cathode, the magnetic field which determines the space charge of the device will be caused to vary synchronously therewith. Increments of energy will therefore be supplied to the oscillating circuit and as a result sustained oscillations will be generated.

Although in the preceding description the magnetic field which determines the space charge of the discharge device is described as being produced by the current flowing through the electron emitter, it is noted that an auxiliary element of good conductive material may be associated with the cathode to produce the magnetic field independently of electron emission. This auxiliary conductor should preferably be positioned interiorly of the cathode and symmetrical with reference to both the cathode and anode.

In Fig. 4 there is shown an evacuated vessel 1 enclosing an auxiliary conductor 18, a cathode 2 and an anode 3. A source 5 supplies heating current to the cathode 2 and also adjustable current of large amplitude to the auxiliary conductor 18, through a coil 4. The current of large amplitude supplied to the auxiliary conductor 18 serves to produce a constant circular magnetic field in the space between the cathode 2 and anode 3 within the discharge device.

Space current is supplied to the discharge device by a source 6 through a path extending from the positive terminal of the source 6 to the anode 3 across the space to the cathode 2 and through a coil 7 to the negative terminal of the source. The coil 7, which is adjustable, is shunted by a variable condenser 8 to constitute a frequency determining circuit. Coil 7 is inductively associated with the coil 4 included in the energizing circuit for the auxiliary conductor 18.

As in the arrangements previously described either the inductance 7 or condenser 8, or both, may be varied to regulate the frequency of the oscillations generated.

Except for the fact that the oscillating current is fed back through the coupling 7-4 to the energizing circuit of the auxiliary conductor 18 to vary the magnetic field within the device in synchronism with the oscillating current generated, this system operates in the same manner as the arrangements previously described.

In its broad aspect this invention is adapted to provide an arrangement wherein the space charge of an electric discharge device, including a cathode adapted to emit electrons independently of gas ionization and an anode, may be increased by establishing a circular magnetic field in the space between the cathode and anode thereof by current flowing through a conductive element within the device and cyclically modifying the magnetic field to vary the space charge and hence the space current flowing between its electrodes.

The discharge device described above is of general application and may therefore be used as an amplifier, repeater, current

regulator, voltage controller, relay or rectifier.

While a particular circuit arrangement and specific details have been set forth for the purpose of completely disclosing the invention, it is to be understood that this invention is not limited thereto, but only by the scope of the appended claims.

What is claimed is:

1. The method of operating a space discharge device having electron-emitting and receiving electrodes and an additional electrode which comprises producing within the device, by current flowing through the additional electrode, a charge for controlling the flow of electronic current.

2. The method of operating a space discharge device having an electron emitter, an anode and an additional electrode, which comprises producing in the space between the emitter and anode, by current flowing through the additional electrode, a magnetic field which controls the flow of electron current within the device.

3. The method of operating a space discharge device having electron-emitting and receiving electrodes and an additional electrode, which comprises producing within the device, by current flowing through the additional electrode, a circular magnetic field for controlling the flow of electronic current.

4. The method of operating a space discharge device having electron-emitting and receiving electrodes and at least one other electrode, which comprises producing within the device, by current flowing through the other electrode, a charge which determines the critical voltage of the device.

5. The method of operating an electron discharge device having an electron-emitting cathode, an anode and an additional electrode, which comprises causing to flow through the additional electrode a current of amplitude large compared to that required to produce electron emission for establishing within the device a charge determining its critical voltage, and varying said charge.

6. A method of operating a self-oscillating system comprising an electron discharge device having an electron-emitter, an anode and at least one other electrode, and circuits associated with said device, which comprises supplying to said other electrode a current of amplitude sufficiently large to establish within the device a charge which determines its critical voltage, generating oscillations in the associated circuits, and cyclically varying said charge by said oscillations.

7. An electron discharge device having an electron-emitting cathode, an anode and an additional electrode adapted to carry a current of such value as to create a magnetic field strong enough to cause electrons to deflect in curved orbits located in planes which pass through the axis of the cathode,

and thereby control the electron current between the cathode and anode.

8. An apparatus for amplifying a variable electric current comprising an electron discharge device in accordance with claim 7, an input circuit including the additional electrode and an output circuit connected in series with the cathode and anode.

9. An oscillation generator comprising an electron discharge device including an electron emitter, an anode and an additional electrode, means for supplying to said additional electrode a current for producing within the device a magnetic field determining its critical voltage, means external to said device for determining the frequency of the oscillations generated, and means for cyclically controlling said magnetic field.

10. An oscillation generator comprising an electron discharge device including an electron emitter, an anode and an additional electrode, means for supplying to said additional electrode a current for producing within the device a magnetic field determining its critical voltage, means external to said device for determining the frequency of the oscillations generated, and means for cyclically varying the currents supplied to said additional electrode.

11. An oscillation generator comprising an electron discharge device including an electron emitter, an anode and an additional electrode, means for supplying to said additional electrode a current for producing within the device a magnetic field determining its critical voltage, means external to said device for determining the frequency of the oscillations generated, and means controlled by said oscillations for cyclically varying the magnetic field.

12. An electric discharge device including an electron emitter, an anode and a current energized means within said device for producing in the space between said emitter and anode a magnetic field determining the critical voltage of the device, and means for cyclically varying the magnetic field.

13. An oscillation generator comprising an electron discharge device having a cathode, an anode and an additional electrode, means for causing to flow through said additional electrode a current of sufficient am-

plitude to produce a controlling field for the discharge between the anode and the cathode, a circuit connecting said anode and cathode, including a frequency determining circuit, and means for coupling said frequency determining circuit to the current supply means for said additional electrode.

14. An oscillation generator comprising an electric discharge device consisting of an evacuated receptacle containing a cathode adapted to emit electrons independently of gas ionization, an anode and an additional electrode; means, including said additional electrode, for producing in the space between said cathode and anode a circular magnetic field determining the critical voltage of the device, means for producing oscillations, provided with frequency determining means, included in the circuit connecting the cathode and anode; and means for varying the magnetic field by said oscillations.

15. An oscillation generator comprising an electric discharge device including an electron emitter, an anode, and a current conductive means, means for supplying to said conductive means a current sufficient to control the electron emission, an oscillation circuit external to said device for determining the frequency of the oscillations generated, and means controlled by said oscillations for varying the amplitude of the current supplied to said conductive means.

16. An oscillation generator comprising an electric discharge device having a cathode, an anode and a current conducting means, means for supplying heating current to said cathode and for supplying to said conducting means energizing current of amplitude large compared to that supplied to the cathode, a circuit connecting said cathode and anode including a frequency determining circuit, and means for coupling said frequency determining circuit to the means for supplying energizing current to said conducting means.

In witness whereof, we hereunto subscribe our names this 16th day of March 100 A. D., 1922.

JOHN B. JOHNSON.
HOMER C. SNOOK.
